Primary Examiner — Holly Baynham*Assistant Examiner* — Rashida C Walshon(74) *Attorney, Agent, or Firm* — Knobbe Martens Olson & Bear, LLP(57) **CLAIM**

The ornamental design for a heel protector, as shown and described.

DESCRIPTION

FIG. 1 is a perspective view of a first embodiment of a heel protector showing our design.

FIG. 2 is a front elevational view thereof. Rear elevational view thereof is identical to the front elevational view.

FIG. 3 is a right-side elevational view thereof. Left-side elevational view thereof is identical to the right-side elevational view.

FIG. 4 is a top plan view thereof.

FIG. 5 is a bottom plan view thereof; and,

FIG. 6 is another embodiment of a bottom plan view thereof. The broken lines in the drawings represent environment that forms no part of the claimed design.

1 Claim, 6 Drawing Sheets(56)
